UNITED STATES PATENT OFFICE.

HERBERT S. JANDUS, OF DETROIT, MICHIGAN, ASSIGNOR TO THE C. G. SPRING & BUMPER COMPANY, OF DETROIT, MICHIGAN, A CORPORATION OF DELAWARE.

BUMPER.

Application filed March 19, 1927. Serial No. 176,666.

This invention relates to vehicle bumpers and more particularly to the provision of a resilient bumper which will afford greater resistance to impacts.

5 Further objects of the invention are to provide a bumper which may be conveniently attached to cars of different widths and one which will present a more attractive appearance.

10 Further objects will be apparent from the following description and the use of the combination of elements covered by the claims.

In the drawings Fig. 1 is a plan view of the bumper and support arms; Fig. 2 shows a 15 front elevation of the bumper; Fig. 3 shows a sectional view taken on the line 3—3 of Fig. 1; Fig. 4 is a sectional view taken on the line 4—4 of Fig. 1.

For convenience the bumper will be described as attached to the front of a vehicle 20 and designation of the "front" and "rear" portions thereof will be made with reference to such attachment, but it is not intended in so doing to restrict the use of the bumper to 25 any particular portion of the machine.

Referring to the drawings, reference characters 1, 2 and 3 denote the bars of the impact element, which may preferably be made of 30 spring steel which has been given a protective coat of nickel or other suitable metal and which are curved and tapered at their ends to form a rearwardly curved narrowed portion at each end of the impact element. The central impact bar 2 is preferably placed in a 35 vertical plane and the bars 1 and 3 are suitably positioned respectively above and below, and in planes inclined to this bar and are so spaced from it as to allow the passage of the bolts 4 and 5 between the bars.

40 The impact bars are held in proper spaced relation by means of clamps 6, 6 at the end portions of the bars and a clamp 7 at the central portion of the bar, which clamps will be more fully described hereinafter.

45 The impact element is supported by means of a rear bar 8 which is pivotally connected at its ends to the clamps 6, 6 and is bent forwardly at its central portion for attachment to the center clamp 7. The support arms 9, 50 9 are connected at their rear ends to the vehicle (not shown) and at their forward ends are pivotally connected to the rear bar 8 by means of the pivot clamps 10, 10 which may be adjusted to the proper width of car by 55 sliding them along the rear bar and clamp-

ing them at the desired point by means of the cap screw 11, 11.

The center clamp is made up of a front plate 7 adapted to bear at its central portion upon the front surface of the impact bar 2 60 and at its end portions upon the front surfaces of the impact bars 1 and 3, a rear plate 7^a adapted to bear at its central portion upon the rear surface of the rear bar 8 and at its end portions upon the rear surfaces of the 65 impact bars 1 and 3, and bolts 4 and 5 passing between the bars and thru the front and rear clamping plates 7 and 7^a. The front surface of the plate 7 provides seats for the heads of the bolts 4 and 5 and the rear surface 70 of the plate 7^a provides seats for the nuts 4^a and 5^a. By tightening these nuts the plates 7 and 7^a are drawn toward each other and thereby clamp the bars 1, 2, 3 and 8 firmly 75 in their proper positions. These plates are 80 preferably of cast metal but they may be of other material, such as spring steel, if desired.

Each end clamp is made up of plates 6 and 6^a having their end portions bent to conform 80 to the desired angular displacement of the impact bars 1, 2 and 3 and adapted to bear upon the front and rear surfaces, respectively, of these bars. The bars 1, 2 and 3 are held in position by means of the bolts 12, 13 85 and 14 passing through the plates 6 and 6^a and thru the bars 1, 2 and 3 respectively. These plates are also preferably made of cast metal but may be of other material if desired. 90

A U-shaped bracket 15 is clamped to the rear surface of the central portion of the plate 6^a by means of the bolt 13 passing through this plate. At each end of the rear bar 8 there is formed an eye 16 adapted to fit 95 around a pin 17 passing through the holes in the end portions of the plate 15, thereby forming a pivotal connection between the rear bar and the impact element.

The ends of the bars 1, 2 and 3 are held together by means of the castings 18, 18 to which they are fastened by the bolts 19. These casting are adapted to bear upon the rear surfaces of the end portions of the impact bars and they prevent the ends of the bars 105 from becoming separated as a result of a permanent bending of the bars. The outer ends of these castings may be enlarged and rounded to present a smooth surface at the end of the impact element which will reduce 110

the tendency of the bars to hook behind obstructions or to scratch objects with which they may come in contact.

A blow struck upon the impact element will 5 be resisted, not only by the bending, tension and compression stresses set up in the impact bar 2 and the rear bar 8, but by the further resistance of the torsional stresses in the two bars 1 and 3, which will tend to be twisted in 10 their supports by the force of the blow.

The curved end portions of the impact element provide for increased rigidity at these portions and present smooth, curved surfaces which will deflect blows directed toward 15 them.

It is apparent that other means for clamping the bars than those described may be substituted without deviating from the scope 20 of the invention, and it is not intended to limit the use to the particular clamping means shown. It is also apparent that the impact element may be made up of two, or more than three, impact bars mounted in planes at different angles to the vertical. Whereas the 25 ends of the impact element are shown in contact with each other and thus forming smooth continuous surfaces, it may be desirable to have spaces between the bars at these portions of the impact element, and also it may be desirable 30 to have the edges of the tapered ends of the bars slightly curved rather than straight as they are shown in the drawings. It is apparent that such variations could be within the scope of the invention and it is 35 not intended to limit that scope to the particular configuration shown and described.

The several impact bars are so positioned as to provide an impact surface which will lie substantially on the arc of a circle. It is 40 apparent that such arc may be increased to as great a portion of the circle as is desired by increasing the number of bars used to make up the impact surfaces. This construction forms, in effect, a section of a tubular bumper 45 and the spacing between the bars and/or the width of the bars may be so reduced as to form substantially a continuous curve as is more clearly shown at the ends of the bumper shown in the drawings. Where the impact 50 bars are in contact as at the ends of the bumper or where the bars are in contact with the bolts, as shown in Fig. 4, a substantially arched impact section is formed which is supported by the plates of the clamps. The 55 rigidity of the impact section is increased by the construction shown.

Having thus described my invention, what I claim is:

1. A vehicle bumper including an impact 60 member made up of separate bars placed in planes inclined to each other, and a rear bar pivotally connected to the end portions of said impact member.

2. A vehicle bumper including an impact 65 member made up of separate bars placed in

planes inclined to each other, a rear bar pivotally connected to the end portions of said impact member and connected at its central portion to the central portion of the impact member.

3. A vehicle bumper including an impact member made up of separate bars placed in planes inclined to each other, a rear bar connected to the end portions of the impact member and to the central portion of the impact 75 member.

4. A vehicle bumper including an impact member made up of separate bars placed in planes inclined to each other, a rear bar connected to the end portions and the central 80 portion of the impact member and means for pivotally connecting the rear bar to support arms attached to a vehicle.

5. A vehicle bumper including an impact member made up of bars placed in planes inclined to each other, a rear bar pivotally connected at its ends to the end portions of the impact member and connected to the central portion of the impact member and means for pivotally connecting the rear bar to support 85 arms attached to a vehicle.

6. An impact element including three bars of spring steel in planes inclined to each other, clamps for holding the bars in proper spaced relation, said clamps consisting of plates adapted to bear upon the front and rear surfaces of the bars and means for drawing adjacent plates toward each other. 90

7. An impact element including a plurality of bars of spring steel placed in planes inclined to each other and having their ends tapered and curved to form smooth surfaces at the ends of the impact element, and clamping means for holding the bars in proper spaced relation. 100

8. An impact element including a plurality of bars of spring steel placed in planes inclined to each other and having their ends tapered and curved to form smooth surfaces at the ends of the impact element, clamping means for holding the bars in proper spaced relation, said clamps including plates adapted to bear upon the front and rear surfaces of the bars and bolts for drawing the plates together. 105

9. An impact element including a bar placed in a substantially vertical plane, one or more bars placed in planes at angles to that of said vertical plane and clamping means for holding the bars in proper spaced 110 relation.

10. An impact element including a spring steel bar placed in a substantially vertical plane, a plurality of spring steel bars in planes other than a vertical plane and clamping means for holding said bars in proper spaced relation. 115

11. A vehicle bumper including an impact element made up of bars placed in planes inclined to each other and having their ends 120

- tapered and curved to form continuous smooth surfaces at the ends of the impact element, and a rear bar connected to the end portions of the impact element.
- 5 12. A vehicle bumper including an impact element made up of bars clamped in planes inclined to each other and having their ends tapered and curved to form continuous smooth surfaces at the ends of the impact element, a rear bar connected to the end portions and to the central portion of the impact element, and support arms pivotally connected to the rear bar. 70
- 10 13. An impact element including a plurality of bars placed in planes inclined to each other, said bars having their ends tapered and bent to form smooth surfaces at the ends of the impact element and having their ends rigidly connected to each other, and clamping means for holding the central portion of the bars in proper spaced relation. 80
- 15 14. In a bumper impact element the combination of a plurality of bars in planes inclined to the vertical, said bars having their end portions tapered and bent to form smooth surfaces at the ends of the impact element, means for connecting the ends of the bars to each other, said means consisting of a plate adapted to be attached to end portions of the rear surfaces of the bars, said plate having an enlarged end portion adapted to extend beyond the ends of the bars, and means for clamping the end portion of each bar to the said plate. 90
- 20 15. A vehicle bumper comprising vertically spaced separate impact bars having their front surfaces in planes inclined to each other and having their end portions adjacent to form a smooth surface. 95
- 25 16. A vehicle bumper comprising impact bars vertically spaced at their central portions and fastened at their end portions by means of connecting plates providing extended smooth curved surfaces. 100
- 30 17. The combination with a bumper impact section made up of bars so supported as to lie substantially in an arc of a circle, of means for supporting said impact bars, said means comprising a bar connected at spaced points to the impact section and having portions intermediate said points of connection spaced rearwardly from said impact section. 110
- 35 18. The combination with a bumper impact section made up of bars supported so as to lie substantially in an arc of a circle, of means for clamping said bars together, and means for supporting said impact section, said last mentioned means comprising a bar pivotally connected at spaced points to the impact section and spaced rearwardly from said impact section intermediate said points of connection. 115
- 40 19. A vehicle bumper comprising an impact section including longitudinally extend-
- ing bars clamped to each other so as to increase the effective thickness of said impact section, and means for supporting said clamped bars from a vehicle said means including a bar connected to the end and middle portions of the impact section. 75
- 45 20. A vehicle bumper comprising an arched impact section including a plurality of longitudinally extending bars clamped together in planes inclined to each other, and means for supporting said impact section said means including a rear bar pivotally connected at its ends to the impact section and arched forwardly intermediate said ends for connection to the impact section. 85
- 50 21. A bumper comprising an impact section including a plurality of longitudinally extending bars having their adjacent edges in contact at the end portions and spaced laterally intermediate such end portions, and means for supporting said impact section. 95
- 55 22. A bumper comprising an impact section including a plurality of bars having their adjacent edges in contact at their end portions and spaced laterally intermediate said end portions, said end portions being curved inwardly, and means for supporting said impact section. 100
- 60 23. A bumper comprising an impact section including a plurality of bars having their adjacent edges in contact at their end portions and spaced apart intermediate said end portions, said end portions being curved inwardly and connected together, and means for supporting said impact section from a vehicle. 105
- 65 24. A bumper comprising an impact section including a plurality of bars clamped together in planes inclined to each other, said bars having their adjacent edges in contact at their end portions and spaced apart intermediate said end portions, and means for supporting said impact section. 110
- 70 25. A vehicle bumper comprising an impact section including a plurality of bars having their central portions in planes inclined to each other and having their edges at one end portion adjacent each other to form a smooth surface at that portion, and means connected to the impact section intermediate its ends for supporting it from a vehicle. 115
- 75 26. A vehicle bumper comprising an impact section including a plurality of bars having their central portions in planes inclined to each other and having their edges at an end portion adjacent each other to form a smooth surface at that portion, means for connecting the ends of the bars, and means connected to the impact section intermediate its ends for supporting said section from a vehicle. 120
- 80 In testimony whereof, I hereunto affix my signature.
